CIRCUIT BREAKER

Fred G. von Hoorn, Nichols, Conn., assignor to
General Electric Company, a corporation of
New York

Application November 19, 1938, Serial No. 241,395

20 Claims. (Cl. 200—88)

My invention relates to circuit breakers, more particularly to automatic electric circuit breakers having current responsive tripping means, and has for its object the provision of a simple, reliable, and inexpensive device of this character.

This invention which is an improvement of the circuit breaker described and claimed in my copending application Serial No. 148,937, filed June 18, 1937, which became Patent No. 2,150,013 on March 7, 1939, has special application to circuit breakers of small physical size such as used in branch electric lighting circuits or as entrance circuit breakers for building and yard lighting.

The device is operable manually to open and close a circuit and is also responsive to excessive current conditions to open the circuit automatically, independently of the operating handle.

In carrying out my invention in one form, I provide a switch member which is mounted for pivotal movement about a plurality of points. One end of this switch member is releasably secured by current responsive means about which it is adapted to pivot between open and closed circuit positions, while the other end carries a switch contact. The switch member is normally opened by moving a handle having a face cooperating with the switch member at a point intermediate its ends.

By interposing an intermediate element or saddle member between the actuating handle and the switch member, a bearing surface is provided for the face of the handle. Cooperating with the intermediate element, which is mounted on the switch member for limiting pivotal movement with respect thereto, is a spring adapted to bias the switch member in closed circuit position to the closed circuit position and at the same time bias the switch member for movement to its open circuit position when released by the current responsive means.

The current responsive means affording automatic circuit breaking upon excessive current conditions in the circuit comprises a pivoted latch member normally holding one end of the switch member, the latch member being movable by the deflection of a thermostatic element engaging a hook projection thereon to free the secured end of the switch member for breaking the circuit. Adjacent the latch member is an element adapted to assist in completing a magnetic circuit for the flux generated by the passage of an electric current through the circuit breaker for magnetically attracting the latch member to an unlatched position, the latch member and the cooperating element being composed of suit-

able magnetizable material. The magnetic means above are adapted to actuate the latch member quickly, upon very excessive current conditions, before the thermostatic element has heated sufficiently to cause automatic thermal unlatching. In this way the circuit is protected both against ordinary excessive currents and also against extremely high surges of current that may cause damage before the thermal means can operate. Both the magnetic means and the thermal means for automatic circuit breaking are mutually assisting under all excessive current conditions.

The biasing spring normally provides a biasing force tending to move the switch member to an open circuit position and also provides a force for automatically returning the switch member, when it is released by the current responsive means, to a position ready to be again secured by the latch member when the thermostatic element has cooled. This resetting movement of the switch member is effected by means of a resetting projection about which the switch member is caused to pivot by the force of the biasing spring, after movement of the switch member to the open position. The biasing spring also causes the handle to be thrown to its open circuit position so that the circuit breaker is ready to be manually reclosed.

For a more complete understanding of my invention, reference should be had to the accompanying drawings, Fig. 1 of which is a longitudinal sectional view of a circuit breaker embodying my invention shown in the manual open circuit position; Fig. 2 is a longitudinal sectional view similar to Fig. 1 but showing the circuit breaker in a manual closed position and showing certain additional parts in full; Fig. 3 is a longitudinal sectional view similar to Fig. 2 but showing the circuit breaker in the overload-tripped open circuit position after operation of the thermal current responsive means; Fig. 4 is a sectional view taken along the line 4—4 of Fig. 1 looking in the direction of the arrows; Fig. 5 is a fragmentary view partly in section similar to Fig. 3 but showing the circuit breaker in the overload-tripped open circuit position after operation of the magnetic current responsive means; Fig. 6 is a perspective view of an operating element of the switch mechanism; Fig. 7 is a fragmentary elevational view partly in section showing another embodiment of my invention; Fig. 8 is a longitudinal sectional view of a further embodiment of my invention showing a circuit breaker in manual closed position;

Fig. 9 is a longitudinal sectional view of the circuit breaker of Fig. 8 in the manual open position; and Fig. 10 is a plan sectional view taken along the line 8—8 of Fig. 8 looking in the direction of the arrows.

Referring to the drawings, I have shown my invention as embodied in a circuit breaker of quite small physical size such as might be used for an entrance switch or circuit breaker for a house, as hereinbefore stated. Of course the size and characteristics of the device will be selected to conform with the desired normal current and overload current to be handled in any particular application. In the form shown, the

circuit breaker comprises an electrically insulating base or casing 10, preferably made from a suitable plastic insulating material, such as a phenolic condensation product, and provided with a metallic strap 11 along the bottom and sides thereof. The top of the casing 10 is covered by a mounting strap 11a suitably attached to the strap 11 and resting on a fiber liner 11b therebeneath, the mounting strap 11a and the liner 11b being provided with an aperture 11c for the actuating means. The strap 11 secures the casing 10 to the mounting strap 11a so that the casing may be conveniently mounted for use.

In this casing is mounted a switch member 12 of the floating type, i. e., it is mounted for pivotal movement selectively about a plurality of points. As shown, the member 12 is mounted by means of a transversely extending guide pin 13 near its middle. Inserted in suitable slots provided therefor in the walls of the casing 10 is a metal U-shaped support 14 having in each leg a groove or slot 15 through each of which projects one end of the guide pin 13. The walls of the slots 15 (only one of which is shown in the drawings) serve as guides for the pin 13 and provide for movement of the switch member about each of its ends as a pivot as well as pivotal movement about the pin 13 as a center.

The switch member 12 is operated between its closed position, shown in Fig. 2, and its open position, shown in Fig. 1, by means of a handle 16 projecting through the aperture 11c and pivotally mounted on a pin 17 whose ends extend through and may be journaled in the walls of the casing 10. This handle has an operating projection or cam face 18 at a predetermined distance from the pin 17 at the lower end of the handle 16 which is in operative relation to move the switch member 12 between its open and closed positions against the bias of a helical spring 19 located under the switch member 12 and exerting a biasing force substantially in the direction of the grooves or slots 15. The spring 19 has its lower end disposed in a molded recess or well 19a in the bottom of the casing 10.

Interposed between the handle 16 and the switch member 12 is a saddle member or element 20 of substantially U-shape having a slotted leg portion 21 at one end, as shown in Fig. 6, through which the switch member 12 extends. The top wall 22 of the slot rests on the upper edge of the switch member 12 in a V-shaped notch 20a provided therefor, as shown in Fig. 5, and forms a pivot for the element 20 on the switch member. The end of one of the legs forming the slotted leg portion 21 is bent over to form a hook 21a fitting under the bottom of the switch member 12 for retaining the element 20 positioned in the notch 20a, thereby preventing longitudinal movement of the element 20 on the switch member 12. The other end of the element 20 is pro-

vided with a projection 23 adapted to engage the end of the helical spring 19 and form a guide and seating projection therefor. This end also has a closed loop or slotted portion 24 surrounding the switch member 12, the slot 24 being of sufficient length to enable the element 20 to pivot freely to a limited extent about the wall 22 of the slotted leg portion 21 in the notch 20a of the switch member 12. The upper end of the slotted portion 24 of the element 20 is provided with a pair of shoulders 24a whose function is hereinafter explained in connection with Figs. 8, 9 and 10.

Since the element 20 is movable pivotally on the switch member 12, in the open circuit position as shown in Fig. 1, the spring 19 preferably bears on the shoulders of the projection 23 of the element 20, the bottom wall of the slot 24 of the element 20 bearing against the underside of the switch member 12 in a notch 12a provided thereunder. Although I prefer to maintain the spring 19 seated entirely on the element 20, it is obvious that by deepening the notch 12a, the spring 19 may be made to bear directly on the switch member 12 in the open circuit position.

In the closed circuit position, shown in Fig. 2, the spring 19 is compressed and forced farther away from the switch member 12 as the element 20 is pivoted in a counterclockwise direction in the notch 20a of the switch member by the handle 16. The intermediate portion of the U-shaped element 20 forms a plane bearing surface 25 for the operating projection or cam face 18 at the lower end of the handle 16. Thus, as shown in Fig. 2, the spring 19 biases the element 20 against the operating projection 18 of the handle 16 to cause the wall 22 of the slotted portion 21 on the element 20 to bear downwardly on the switch member 12 in the notch 20a for holding the switch member in a closed circuit position with its right-hand end secured by a current responsive element, shown as a pivoted latch 26. When the handle is moved to the left to the open position, as shown in Fig. 1, the spring 19 moves the element 20 upward with respect to the switch member 12, the right-hand end of the member 20 pivoting in the notch 20a of the switch member, until the bottom wall of the slot 24 of the element 20 engages the switch member in the notch 12a, whereupon the spring force moves the switch member about its right-hand end on the latching portion of the latch 26 as a pivot to the open circuit position. The extreme open circuit position of the actuating handle 16 is determined by an extension from the casing 10 forming a stop 29a which engages a face 29 of the handle and limits its movement in the counterclockwise direction.

Likewise, when the handle is moved to the right to the closed position, as shown in Fig. 2, from the open position, the projection or cam face 18 engages the element 20 and causes switch member 12 through the pressure of the right-hand end of the element 20 in the notch 20a to move downwardly about the pivot point on the latch 26 to bring a movable contact 27 at the left-hand end of the switch member 12 into engagement with a stationary contact 28 secured to the base 10. During the closing movement, the force of the handle 16 is transmitted to the switch member by the edge of the element 20 bearing on the bottom of the notch 20a, the spring 19 retaining the switch member and element 20 in substantially the same relative positions as in the open circuit position shown in Fig. 1. After the contacts 27 and 28 engage,

further movement of the handle 16 to the right depresses the left end of the element 20, i. e., the element 20 pivots slightly in a counterclockwise direction, to tension or stress the spring 19 independently of the movement of the switch member 12 and thereby cause the spring 19 to apply a force on the switch member in its closing direction at the notch 20a by the lever action about the fulcrum provided by the cam face 18 of the handle. In effect, the cam face 18 of the handle 16 acts as a fulcrum for the element 20 to give a lever action to this element for transposing the upwardly acting force of the spring 19 into a downwardly acting force on the switch member. In this manner, the contacts 27 and 28 are biased into engagement by the force of the spring 19 acting through the element 20 when the switch member 12 is in the closed circuit position.

20 When the handle is moved toward the left to the open position as shown in Fig. 1, the cam face 18 is moved away from the bearing surface 25 on the element 20 so as to allow the switch member 12 to be moved to the open position by the helical spring 19; the element 20 then being permitted to rest on another face 29 provided therefor on the handle 16 closer to the pin 17. It will be noted that the cam face 18 is so disposed that a force perpendicular thereto at its middle passes substantially through the pivot 17 whereby the force applied by the switch member 12 secures the handle 16 in its closed circuit position, the extreme closed circuit position of the handle 16 again being determined by engagement of the face 29 of the handle on the stop 29a as was the case for the open circuit position.

For guiding the switch member 12 in its pivotal movement and for avoiding lateral movement thereof, I have also provided the guide member 29b in the form of an inverted U of insulating material inserted transversely of the casing 10. The guide member 29b fits over the switch member 12 near its left-hand end, the switch member being slideable between the legs thereof. The vertically extending guide member 29b also serves as a wall to confine the arc from the contacts 27 and 28 in the left-hand portion of the casing 10.

The current responsive means, actuated by excessive current conditions for disengaging the switch member 12 from a latching aperture 30 in the latch 26, comprises both thermally and magnetically operable means described hereinbelow. The thermally operable means consists of a thermostatic element, such as the bimetallic strip 31, which is secured by a rivet 32 to a terminal projection 33 at the top of the casing 10 and which extends through an aperture 34 in the upper portion of the latch 26 downwardly at the other side to engage a hook projection 35 at the lower end of the latch 26. Threaded adjusting means, such as a screw 36 supported by a bent extension of the terminal projection 33 and adapted to be screwed into bearing relation on the thermostatic element 31, is provided for adjusting the normal position of the thermostatic element 31. As best illustrated in Fig. 4 (shown by dotted lines), the terminal projection or support 33 comprises a metal strip having a portion extending transversely in the top of the casing 10 on which the thermostatic element 31 and the adjusting screw 36 therefor is mounted. Another portion of the support 33 forms a terminal 38 mounted outside the casing 10 on a suitable projection of the outer casing wall. The

support 33 extends from the terminal 38 into the casing 10 and upwardly along the right-hand wall of the casing forming both a support for and an electrical conductor to the thermostatic element 31. A spring strip 37 is disposed between the latch 26 and the thermostatic element 31 for biasing the hook 35 on the end of the latch 26 into engagement with the lower end of the thermostatic element.

Upon heating the thermostatic strip 31 by passage of a predetermined excessive current therethrough, the thermostatic strip 31 is caused to deflect away from the switch member 12. The circuit through the switch is from the terminal 38 shown in Fig. 4 through the support 33, thermostatic strip 31, a conductor 39 attached to the lower end of the thermostatic strip 31, the switch member 12, the contacts 27 and 28, to a second terminal 38a (shown in Fig. 10) similar to the terminal 38 to which the stationary contact 28 is electrically connected. Deflection of the thermostatic strip 31 causes pivotal movement of the latch 26 about the projections or ears 40 at the upper end thereof, the projections 40 being pivotally mounted in appropriate recesses in the walls of the casing 10. Upon sufficient pivotal movement in a counterclockwise direction, the latch 26 is disengaged from the right end of the switch member 12, and automatic circuit breaking occurs in a manner to be explained hereinafter. As shown in Fig. 3, deflection of the thermostatic strip 31 has pivoted the latch 26 out of engagement with the switch member 12, and the contact 27 has moved to its open position.

The magnetic tripping or unlatching means comprises the pivoted latch 26 and a cooperating member 42 disposed adjacent the latch and suitably supported in the casing 10. The latch 26 and the member 42 are formed of suitable magnetizable material arranged to provide a magnetic circuit for the flux generated by the passage of an electric current through the thermostatic strip 31. As illustrated in Fig. 10, the member 42 consists of a U-shaped element, the legs of the U coacting with the edges of the latch 26, there being air gaps 41 between them, to complete the magnetic circuit. The member 42 is disposed adjacent the latch 26 in parallel relation therewith and in such position that the thermostatic strip 31 extends between its legs. When the thermostatic strip 31 is energized by an excessive current flowing therein, the lines of magnetic flux will tend to concentrate in the magnetic circuit provided therefor, and, if the flux is of sufficient magnitude, the latch 26 will be drawn by magnetic attraction against the normally restraining bias of the spring strip 37 toward the U-shaped member 42. As shown in Fig. 5, the latch 26 may be magnetically attracted and the switch member 12 disengaged therefrom very quickly, during a condition of excessive current, and before the thermostatic strip 31 has heated and deflected sufficiently to cause the switch member 12 to be thermally disengaged. The magnetic forces attracting the latch 26 need only be strong enough to overcome the bias of the spring strip 37 and the frictional engagement in the aperture 30 between the right end of the switch member 12 and the latch 26.

As hereinbefore described, the switch member 12 is normally operable between open and closed circuit positions by movement of the handle 16, the switch member 12 pivoting about a fulcrum

edge of the aperture 30 of the latch 26. For preventing longitudinal displacement of the switch member 12 on the fulcrum edge of the aperture 30 to avoid possible changes in latching adjustment, the lower portions of the concentric grooves 15 are given a curvature whose center is the fulcrum edge of the aperture 30. The switch member 12 is thereby restrained to pivotal movement only, when actuated between normal open and closed circuit positions, the longitudinal positioning of the switch member with respect to the fulcrum edge of the aperture 30 remaining as originally adjusted.

Further, on each of the legs of frame member 14 I have provided a slot 14a on the lower left-hand side, as seen in the drawings, the object of each slot 14a being to form a prong 14b, which is bent out slightly to form a wedge for the frame 14 when the frame 14 is inserted in the recesses 20 provided therefor in the walls of the casing 10. The wedging effect of the prongs 14b fixes the frame 14 securely in the base 10 and takes up any looseness between the frame and the base, thereby definitely locating the frame 14 and the 25 grooves 15 therein with respect to the casing 10 and the thermostat 31. By thus eliminating lost motion between the switch member 12, the thermostat 31 and the latch 26, the device assumes a more positive tripping characteristic and hence is 30 more reliable for any given initial adjustment. Also the prongs 14b exert a locking action on the walls of the groove, tending to dig into the walls and thereby prevent withdrawal of the frame member.

Upon a condition of excessive current, the current responsive means, magnetic, thermal, or both, causes the latch 26 to be disengaged from the secured end of the switch member 12. From a closed circuit position, as shown in Fig. 2, the latch 26 is moved in a counterclockwise direction to the position shown in Figs. 3 and 5. The switch member 12 is then rotated in a clockwise direction around the tip 18 at the lower end of the handle 16 until it strikes a resetting projection 44 in the upper left-hand portion of the casing 10. The resetting projection or stop 44 is made of insulating material preferably as an insert mounted in the casing 10, or it may be a projection integral with the casing wall. During the rotative movement of the switch member 12, the saddle element 20 pivots with respect to the switch member about the fulcrum 22, also in a clockwise direction, until the lower edge of the slot 24 abuts against the switch member in the slot 12a. When the saddle element 20 has assumed a sufficiently steep incline with respect to the tip 18 of the handle 16, as a result of the aforementioned clockwise rotation by the force of the spring 19 on the shoulders of the extension 60 23 of the element 20, the handle is rotated in a counterclockwise direction toward the "off" position of the handle.

On striking the resetting projection 44, which is to the left of the spring 19, the movement of the switch member 12 is reversed to counterclockwise around the projection 44 as a pivot, and continues until the face 29 of the handle 16 abuts the stop 29a which prevents further rotation of the handle. At this point in the operation, the right-hand end of the switch member is in position to register with the aperture 30 in the latch 26 and dispose itself therein after cooling of the thermostatic strip 31. Thereafter, the circuit breaker is in the normal open circuit position, as shown in Fig. 1, and may be manually actuated

to the closed circuit position, as shown in Fig. 2, by moving the handle 16 to the right.

As previously explained, the handle 16 is pivoted on the pin 17 above the ends of the support member 14 which is inserted into the casing 10. As a further assurance that the member 14 shall be held in position, in addition to the locking prongs 14b, I have provided a trunnion projection 43 on each side of the handle 16. Should the support member 14 seek to rise out of the casing 10, the trunnion projections 43 are adapted to bear on the upper edges of the legs of the support member 14 to assist in retaining the support member 14 in position in the casing 10 against the force of the spring 19 which seeks to lift the support member 14. Each trunnion projection 43 has a curved bearing surface 43a which normally moves closely adjacent the upper edges of the support 14 with a small clearance therebetween so as to be engaged thereby and prevent any substantial upward movement of the support 14 in all positions of the handle should the support seek to rise.

Referring now to Fig. 7, I have shown another embodiment of my invention having primarily the same construction as the circuit breaker previously described, but having means for wedging the guide pin for the switch member between a portion of the supporting frame and the casing under the bias of the operating spring. As shown, in a suitable casing 50, a U-shaped frame 50a is provided having the grooves 51 in the legs thereof to receive a pin 52 extending transversely from the sides of a switch member 53. Each end of the pin 52 is slidable in one of the grooves 51 in each side of the frame 50a, a portion of the grooves being curved to avoid longitudinal movement of the switch member 53 while pivoting about a latch member (not shown) during manual switching. Secured to the bottom of the frame 50a, for pivotally supporting the frame in the casing 50, is a laterally extending arm 54 the end of which rests on a pivot projection 55 on the floor of the casing 50. The frame 50a is biased in a clockwise direction by an operating spring 56 supported between the arm 54 and the saddle member 20 carried by the switch member 53. In each wall of the casing 50 is a recess shaped to form a ledge 57 substantially of the same outline as the right edge of the curved grooves 51 in the frame 50a, the legs of the frame 50a being positioned adjacent the side walls of the casing 50.

In operation of the circuit breaker shown in Fig. 7, the compression force of the operating spring 56 is used to wedge the slideable pin 52 between the left-hand edge of the groove 51 and the ledge 57 as the pin 52 is slidably moved in the groove 51 by movement of the switch member 53. This arrangement utilizes the spring force of the operating spring 56 both for operating purposes and for biasing the pin 52 against the ledge 57 of the casing. It has the advantage of providing a more uniform pressure on the pin 52 whereby binding of the pin 52 is avoided, as well as positioning the pin 52 and the switch member 53 definitely with respect to the casing 50 and the thermostatic latching means previously described. In this manner, variations in operation of the circuit breaker for a predetermined setting of the latching means are minimized, and the device assumes a more positive tripping characteristic.

In Figs. 8, 9, and 10 I have illustrated a further modification of the circuit breaker frame 75

construction which is well adapted to minimize variations in calibration of the overload responsive latching means by definitely positioning the switch member with respect to the casing and therefore with respect to the latching means which is supported by the casing. In this modification, a casing 60 having a pair of side walls 61 is provided. Each of the two side walls 61 includes a vertically extending recess 62 in which the extending portions of a U-shaped frame or support member 63 are loosely contained. The bottom of the U-shaped frame 63 rests directly on the floor of the casing 60 and has a laterally extending arm 64 projecting at one side therefrom longitudinally of the casing 60. A recess 65 in the floor of the casing 60 immediately below the arm 64 of the frame 63 provides a fulcrum edge extending transversely of the casing on which the frame 63 is biased for pivotal movement in a counterclockwise direction by the operating spring 19 which is seated on the upper surface of the arm 64 of the frame.

As in the other embodiments of my invention shown in Figs. 1 to 7, inclusive, I have in Figs. 8, 9 and 10 provided the switch member 12 pivotally supported on the transversely extending pin 13 which is slidably mounted in the concentrically curved grooves 15 in the vertically extending portions of the frame 63. The switch member 12 carries the saddle member 20 which cooperates with the operating spring 19 and the lower end 18 of the handle 16 for enabling manual operation of the switch member 12 to the closed and open circuit positions shown in Figs. 8 and 9 as hereinbefore explained in connection with Figs. 1 and 2. In manual operation, the switch member 12 pivots about the fulcrum edge of the aperture 30 in the latch member 26 between open and closed circuit positions.

Referring to Fig. 6, it will be noted that the saddle member 20 has a pair of shoulders 24a adjacent the upper end of the slotted portion 24 of this member. In the present embodiment of my invention, I have provided a pair of projections 66 extending from the walls 61 of the casing 60 against which the shoulders 24a are adapted to abut in the closed circuit position of the switch member 12. As seen in Fig. 8, the shoulders 24a of the saddle member 20 are in abutting relation with the projections 66. The frame 63 is biased in a counterclockwise direction by the operating spring 19. The bias of the frame is transmitted to the pin 13 and through it to the switch member 12, thence through the V-shaped fulcrum 20a for the saddle member 20 to the saddle member. The shoulders 24a of the saddle member 20 are thrust against the vertically disposed surfaces of the projections 66. In the closed position of the breaker, the saddle member 20 and therefore the switch member 12 assume a definite relation with respect to the casing and also with respect to the latch member 26 which is attached to the casing 60 and adjustable with respect thereto by the adjusting screw 36.

The projections 66 only extend upwardly a short distance above the position that the shoulders 24a of the saddle member 20 assume in the closed circuit position. When the handle 16 is moved to the left to permit the switch member 12 to pivot to the open circuit position shown in Fig. 9 about the latching aperture 30, the saddle member 20 rises free of the restraining projections 66. Thereafter, the frame 63 is free to pivot still further in a clockwise direc-

tion to a very limited extent. The limit of this pivotal movement is determined by the clearance provided between the edges of the recesses 62 and the extending portions of the frame 63.

With the switch member 12 in the open position, the handle 16 may be moved to the right. The force of the handle is transmitted to the switch member 12 through the saddle member 20. As the switch member 12 approaches the closed position, the shoulders 24a of the saddle member 20 are forced into surface engagement with the projections 66. Further movement of the handle 16 to the right causes the cam face 18 thereon to pivot the saddle member 20 slightly in a counterclockwise direction with respect to the switch member 12, at the same time forcing the saddle member and the switch member bodily to the right against the bias of the frame 63. The slight pivotal movement of the saddle member pre-tensions the operating spring 19 causing it to transmit a force at the fulcrum point 20a of the switch member in the circuit closing direction while at the same time biasing the switch member for movement toward the open circuit position upon release of the latch 26. The movement of the switch member 12 bodily to the right disposes this member with respect to the casing so that its right-hand end always assumes a predetermined position on the latch 26 in the closed position of the switch member. In this manner variations in calibration of the overload responsive means for a given setting are minimized, and the device assumes a more positive tripping characteristic.

Although I have shown the element 20 as a substantially U-shaped member (Fig. 6), it will be understood, of course, that I do not wish to be limited thereto since many modifications in the form or shape of this element may be made whereby it will still perform the various functions herein denoted. I therefore contemplate by the appended claims to cover the various modifications of the circuit breakers illustrated as fall within the true scope and spirit of my invention.

What I claim as new and desire to secure by Letters Patent of the United States, is:

1. A circuit breaker comprising a switch member mounted for pivotal movement, circuit controlling means operated by said switch member, means for actuating said switch member from an open circuit to a closed circuit position, means for biasing said switch member, current responsive means releasably securing one end of said switch member whereby movement of said actuating means moves said switch member about said secured end, and an element interposed between said switch member and said actuating means carried by said switch member having a portion engaging said switch member, a portion engaging said biasing means and another portion thereof engaging said actuating means whereby said switch member, said biasing means and said actuating means are operatively interconnected.

2. A circuit breaker comprising a stationary contact, a cooperating movable contact, a switch member for moving said movable contact between closed and open circuit positions, current responsive means normally releasably retaining one point of said switch member in a predetermined position serving as a pivot about which said switch member is normally rotatable between closed and open circuit positions, an actuating member operatively connected with said

switch member to move said switch member about said pivot point between closed and open circuit positions, a spring applying a biasing force on said switch member, and an element interposed between said switch member and said actuating member having a portion thereof forming a bearing surface for said actuating member and another portion cooperating with said spring for applying said biasing force to move said switch member about said pivot point to one of said positions when said switch member is in said closed circuit position and at the same time biasing said switch member to move upon release of said pivot point by said current responsive means and move said movable contact toward said open circuit position.

3. A circuit breaker comprising a switch member mounted for pivotal movement, circuit controlling means operated by said switch member, means for actuating said switch member from an open to a closed position, means for biasing said switch member, current responsive means releasably securing one end of said switch member whereby movement of said actuating means moves said switch member about said secured end, and an element interposed between said switch member and said actuating means forming a bearing surface for said actuating means, a portion of said interposed element bearing on said switch member and another portion thereof forming a seating projection for said biasing means, said element biasing switch member to said closed position when said actuating means is in said closed position and adapted to move said switch member and said actuating means to said open position upon release of said switch member by said current responsive means.

4. A circuit breaker comprising a switch member mounted for pivotal movement, a handle, means pivotally mounting said handle, said handle being provided with a face located a predetermined distance from the pivot of said handle for actuating said switch member from an open to a closed circuit position in dependence upon the position of said handle, means biasing said switch member toward said handle, means including a U-shaped member interposed between said switch member and said handle having the legs of the U slotted to fit over the switch member transversely thereof, the middle portion of the U forming a bearing surface for said handle, one end of the U forming a seating projection for said biasing means, and the other end of the U pivotally bearing on said switch member, load responsive means releasably securing one end of said switch member whereby movement of said handle moves said switch member about said secured end, and circuit controlling means operated by said switch member.

5. A circuit breaker comprising a switch member mounted for pivotal movement, a switch contact on one end of said switch member, a spring for biasing said switch member to an open circuit position, an actuating member for moving said switch member to a closed circuit position against the force of said spring, a stationary contact engaged by said movable contact when said switch member is in its closed circuit position, and an intermediate element between said actuating member and said switch member normally biased by said spring to a predetermined position with respect to said switch member but moved by said actuating member with respect to said switch member after engagement of said contacts to tension said spring independently of

movement of said switch member and thereby cause said spring to apply a force to said switch member in its closing direction.

6. A circuit breaker comprising a switch member mounted for pivotal movement, a switch contact on one end of said switch member, current responsive means releasably securing the other end of said switch member, a spring for biasing said switch member to an open circuit position about said other end as a pivot, an actuating member for moving said switch member about said other end to a closed circuit position against the force of said spring, a stationary contact engaged by said movable contact when said switch member is in its closed circuit position, and an intermediate element between said actuating member and said switch member normally biased by said spring to a predetermined position with respect to said switch member but moved by said actuating member with respect to said switch member after engagement of said contacts to tension said spring independently of movement of said switch member and thereby cause said spring to apply a force to said switch member in its closing direction.

7. A circuit breaker comprising a switch member mounted for pivotal movement, a switch contact on one end of said member, current responsive means releasably securing the other end of said switch member, a spring for biasing said switch member to an open circuit position about said other end as a pivot, an actuating member for moving said switch member about said other end to a closed circuit position against the force of said spring, a stationary contact engaged by said movable contact when said switch member is in its closed circuit position, and an intermediate member between said operating member and said switch member having one end pivoted on said switch member, an intermediate portion bearing on said actuating member and its other end engaging said spring to cause said spring to supply a force to hold said switch member in its closed circuit position when said actuating member is moved to a closed circuit position after engagement of said contacts.

8. A circuit breaker comprising a support having a pair of extensions provided with oppositely disposed concentric grooves, switching means including a switch member movable on said support, transversely extending guide members on said switch member slidably in said grooves, means for actuating said switch member from an open to a closed circuit position, current responsive means releasably securing an end of said switch member, and a spring for biasing said switch member to an open circuit position about a portion of said current responsive means as a fulcrum, a portion of said grooves being formed on a curve having the fulcrum on said current responsive device as a center for preventing longitudinal movement of said switch member when turning about said fulcrum.

9. A circuit breaker comprising a casing, a support inserted in said casing provided with oppositely disposed concentric grooves, switching means including a switch member movable on said support, transversely extending guide members secured to said switch member intermediate the ends thereof and slidable in said grooves, a handle, means pivotally mounting said handle, said handle being provided with a face located a predetermined distance from the pivot of said handle for actuating said switch member from an open to a closed circuit position in de-

pendence upon the position of said handle, a current responsive device normally securing one end of said switch member, a spring biasing said switch member to an open circuit position about 5 a portion of said current responsive device as a pivot, a portion of said grooves being formed on a curve having the pivot portion of said current responsive device as a center for preventing longitudinal movement of said switch member on 10 said pivot, and an element interposed between said switch member and said handle having a portion engaging said switch member, a portion forming a seating projection for said spring and another portion thereof forming a bearing surface 15 for said handle.

10. A circuit breaker comprising a casing, a support inserted in said casing having a pair of extensions provided with oppositely disposed concentric grooves, switching means including a 20 switch member movable on said support, transversely extending guide members on said switch member slidable in said grooves, means for actuating said switch member from an open to a closed circuit position including a pivoted handle 25 having at least one trunnion projection thereon disposed to cooperate with at least one of said extensions on said support for retaining said support positioned in said casing.

11. A circuit breaker comprising a casing, a 30 support inserted in said casing having a pair of extensions provided with oppositely disposed concentric grooves, switching means including a switch member movable on said support, transversely extending guide members on said switch member slidable on said grooves, current responsive means releasably securing an end of 35 said switch member, a handle pivotally mounted in said casing for actuating said switch member from an open to a closed circuit position about 40 said secured end of said switch member as a pivot, and means including a pair of projections on said handle having a curved bearing surface disposed to bear on the ends of said extensions for retaining said support positioned in said casing 45 should said support seek to rise in said casing.

12. A circuit breaker comprising a casing, a support inserted in said casing having a pair of extensions provided with oppositely disposed concentric grooves, switching means including a 50 switch member movable on said support, transversely extending guide members on said switch member slidable on said grooves, a handle pivotally mounted in said casing for actuating said switch member from an open to a closed circuit position, means including a pair of projections 55 on said handle having a curved bearing surface disposed to bear on the ends of said extensions for retaining said support positioned in said casing, current responsive means releasably securing 60 an end of said switch member, and a spring for biasing said switch member to an open circuit position about a portion of said current responsive means as a fulcrum, a portion of said grooves in said extensions on said support being 65 formed on a curve having the fulcrum on said current responsive device as a center for preventing longitudinal movement of said switch member when turning about said fulcrum.

13. A circuit breaker comprising a casing, a 70 support inserted in said casing having a pair of extensions provided with oppositely disposed concentric grooves, said support having prong members thereon adapted to prevent movement of 75 said support longitudinally of said casing and to securely position said support therein, switch-

ing means including a switch member movable on said support, transversely extending guide members on said switch member slidable in said grooves, means for actuating said switch member from an open to a closed position, current 5 responsive means releasably securing an end of said switch member, and a spring for biasing said switch member to an open position about a portion of said current responsive means as a 10 pivot, a portion of said grooves being formed on a curve having the pivot on said current responsive means as a center for preventing longitudinal movement of said switch member when turning about said pivot.

14. A circuit breaker comprising a casing, a 15 support inserted in said casing having a pair of extensions provided with oppositely disposed concentric grooves, said support having prong members thereon adapted to prevent movement of said support longitudinally of said casing and 20 to securely position said support therein, switching means including a switch member movable on said support, transversely extending guide members on said switch member slidable in said grooves, means for actuating said switch member 25 from an open to a closed circuit position including a pivoted handle having at least one trunnion projection thereon cooperating with at least one of said extensions on said support whereby said support is retained positioned in said casing. 30

15. A circuit breaker comprising a casing having a pair of ledges in the side walls thereof, a support pivotally mounted in said casing having a pair of extensions provided with a groove adjacent each of the said ledges, switching means 35 including a switch member movable between closed and open circuit positions having transversely extending projections slidable in said grooves and along said ledges, means for biasing said support in a predetermined direction for 40 wedging said projections on said switch member between said ledges and an edge of said grooves, means for actuating said switching means, and current responsive means mounted in said casing releasably securing one end of said switch 45 member.

16. A circuit breaker comprising a casing, a support pivotally mounted in said casing having a pair of extensions provided with oppositely disposed concentric grooves, means including a 50 ledge formed on each side of said casing concentric with an edge of said grooves, switching means including a switch member movable on said support, transversely extending guide members on said switch member slidable in said 55 grooves and along each of said ledges in said casing, means for actuating said switch member from a closed to an open circuit position, a current responsive device releasably securing an end of said switch member, and means including 60 a spring for biasing said switch member to an open circuit position about a portion of said current responsive device as a fulcrum and for biasing said support in a predetermined direction for wedging said guide members between 65 an edge of said groove and said ledges on said casing, a portion of said grooves on said support being formed on a curve having the fulcrum on said current responsive device as a center for preventing longitudinal movement of 70 said switch member when turning about said fulcrum.

17. A circuit breaker comprising a casing, a support pivotally mounted in said casing having a pair of extensions provided with oppositely 75

disposed concentric grooves, means including a ledge formed on each side of said casing concentric with an edge of said grooves, switching means including a switch member movable on said support, transversely extending guide members secured to said switch member and slideable in said grooves and along each of said ledges in said casing, a handle for actuating said switch member, current responsive means including a latch member pivotally mounted in said casing normally releasably securing one end of said switch member, a spring biasing said switch member for movement about a portion of said current responsive means as a pivot, said spring biasing said support in a predetermined direction for wedging said guide members between an edge of said grooves and said ledges on said casing for positioning said switch member with respect to said casing, and means including an element interposed between said switch member and said handle having a portion engaging said switch member, a portion forming a seating projection for said spring, and another portion thereof forming a bearing surface for said handle.

18. A circuit breaker comprising a casing, a support pivotally mounted in said casing having a pair of extensions provided with concentric grooves, switching means including a switch member having transversely extending projections slideable in said groove and movable between open and closed circuit positions, current responsive means mounted in said casing releasably securing a point of said switch member, actuating means for moving said switch member about said point between closed and open circuit position, a spring biasing said support in a predetermined direction and applying a biasing force to move said switch member about said pivot point to one of said positions when said switch member is in said closed circuit position and at the same time biasing said switch member for movement when released by said current responsive means to move said switch member toward open circuit position, and means including a projection on said casing for positioning said switch member with respect thereto for minimizing variations in the release of said switch member by said current responsive means when said switch member is in the closed circuit position.

19. A circuit breaker comprising a casing, a

support pivotally mounted in said casing having a pair of extensions provided with concentric grooves, switching means including a switch member movable on said support, transversely extending guide members mounting said switch member and slideable in said grooves, current responsive means disposed in a predetermined relation with respect to said casing releasably securing a point on said switch member, means for actuating said switch member between open and closed positions about said current responsive means as a pivot including a saddle member on and in engagement with a portion of said switch member, and means in abutting relation to said saddle member in the closed position of said switch member for positioning said switch member with respect to said casing for minimizing variations in the release of said switch member by said current responsive means.

20. A circuit breaker comprising a casing, a support pivotally mounted in said casing having a pair of extensions provided with concentric grooves, switching means including a switch member movable on said support and having transversely extending guide members slideable in said grooves, current responsive means mounted in said casing releasably retaining a point on said switch member, a handle for actuating said switch member between open and closed circuit positions about said current responsive means as a pivot, a spring biasing said support in a predetermined direction and applying a biasing force to move said switch member about said point to said closed circuit position when said switch member is in said closed circuit position at the same time biasing said switch member for movement when released by said current responsive means to move said switch member toward open circuit position, a saddle member interposed between said handle and said switch member pivotally engaging a point on said switch member for applying the force of said handle thereto, and means including a pair of projections on said casing for cooperating with a pair of shoulders on said saddle member for positioning said saddle member with respect to said casing in the closed circuit position of said switch member, thereby positioning said switch member with respect thereto for minimizing variations in the release of said switch member by said current responsive means.

FRED G. von HOORN.

DISCLAIMER

2,184,372.—*Fred G. von Hoorn*, Nichols, Conn. CIRCUIT BREAKER. Patent dated December 26, 1939. Disclaimer filed October 19, 1940, by the assignee, *General Electric Company*.

Hereby enters this disclaimer to claim 8 of said Letters Patent.
